TIME CONTROL SWITCH

Earl C. Williams, Syracuse, N. Y., assignor to
 Easy Washing Machine Corporation, Syracuse,
 N. Y., a corporation of Delaware

Application September 29, 1951, Serial No. 248,931

4 Claims. (Cl. 200—33)

1

This invention relates to sequential time control switches, and more particularly to one affording selection of operating cycles adapted for automatic washing machines.

In clock or motor driven timers employing multiple cams for actuating, for example, switches for carrying out a cycle of operations, provision for varying the cycle of operations has been made by permitting the cams to be manually advanced so as to eliminate a part of the cycle. In this manner, by manual actuation during the cycle, a different cycle is obtained. Such manual shifting of the cams is instantaneous in character, and during the shift, actually rotates the cams and actuates the various switches momentarily, which would have normally been actuated slowly by the timer motor.

The present invention is directed to providing a timer in which a choice of different cycles of operation may be made at the outset, and in which either cycle may be shortened through manual advance at any stage of either cycle selected. The invention is also directed to a safety circuit breaking feature, which opens all circuits during the instant of manual advance, so that during the manual advancing operation, the cam actuated switches are ineffective to momentarily actuate circuits not desired, and which in effect are being eliminated by the manual advance.

The above and other novel features of the invention will appear fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a side elevation of the timer with parts shown in section;

Figure 2 is an enlarged transverse sectional view taken substantially on the line 2—2 of Figure 1;

Figure 3 is an enlarged section taken substantially on the line 3—3 of Figure 1;

Figure 4 is a sectional view taken substantially on the line 4—4 of Figure 1;

Figure 5 is a broken section taken substantially on the line 5—5 of Figure 1; and

Figure 6 is a section taken substantially on the line 6—6 of Figure 1.

Referring to Figure 1, there is shown a timer comprising a housing or frame 10, mounted on

2

a base-supported bracket 11. The timer comprises a plurality of disk cams 12 and cam-actuated followers 14 with contacts 15, the cams being mounted rigidly upon a shaft 16 driven by a timer motor 18 through a suitable gear train. The timer motor 18 and gear train 20 provide a slow motion, or step by step motion, and drives the shaft 16 through pinion 22 and gear 24. The timer motor and gear train may be of the type disclosed in the patents to Hall Nos. 2,313,064 and 2,227,133. The gear train, as is well understood in the art, includes an overrunning clutch or ratchet, whereby the cam shaft 16 may be rotated in advance of the timer motor drive by manual means.

As shown in Figure 1, the cams are arranged in pairs, each adjacent pair of cams being provided with a single cam follower, there being provision as will be hereinafter described, for moving the cam shaft axially to bring one or the other set of alternate cams into operative engagement with the cam followers. With such an arrangement, it is possible to select two different cycles or sequences of operations to be controlled by the two different sets of cams. In the automatic control of laundry appliances, such as washing machines and the like, it is desirable not only to provide different cycles of operation, but also to provide for shortening the cycle by manually advancing the cams to omit or shorten a particular stage of the cycle.

When advancing the cycle, it is desirable that the circuits opened or closed by the cams, as well as the circuit to the timer motor, be de-energized while the advance is taking place. For this purpose, the cam shaft 16 is coupled to the manual control knob 26 through a resiliently biased lost motion device 28. The knob 26 is keyed as at 30 to the shaft 32, the key comprising a resilient L-shaped wire, the radial portion 31 passing through a hole 33 in the shaft and engaging a slot 35 in the knob collar 37. The horizontal portion is arched and lies in a groove 39 in the shaft, the arc resiliently gripping the bore of the collar 37. Such shaft extends into a collar 34 and is keyed as at 36 thereto, the key comprising a transverse pin 41 positioned in an endwise diametral slot 43 in the collar. A split ring and washer 45 and 47, respectively, hold the pin within the slot. The elongated collar extends over the end of the shaft 16, and as shown in Figure 4, is provided with a transverse slot 38 in which is loosely positioned a pin 40 extending diametrically through the shaft 16. The slot 38 and pin 40 afford a range of lost motion be-

tween the shaft 32 and collar 34, and the shaft 16. Secured to the shaft 16 is a collar 42, the collar 42 and the collar 34 being composed of insulating material. Each of the collars carries a shallow flanged disk 44 and 46 rigidly mounted therein, the flanges 48 and 50 being slightly spaced from one another but extending toward each other to form a housing for a pair of contacts 52 and 54, one of the contacts being carried by the disk 44 and the other by the disk 46.

The flanges 48 and 50 serve as collecting rings and are engaged by stationary brushes 56 and 58 supported on a non-conducting member 60 secured to the timer bracket 11. The collars 34 and 42 are provided with coaxial facing recesses 62 and 64 in which is positioned a torsion spring 65 and through the coils of which the shaft 16 extends. Such coil spring has substantially radially extending end portions 66 and 68 engaging in slots 70 and 72 in the facing ends of the collars 34 and 42, such slots extending radially from the recesses 62 and 64. The coil spring 65 is adapted to torsionally twist the collars with respect to each other, so as to resiliently cause the contacts 52 and 54 to bear against one another. At the same time, the coil spring is sufficiently light so that as the shaft 32 is turned by the knob 26, the contacts 52 and 54 separate before the friction of the followers 14 on the cams 12 will permit the shaft 16 to rotate. After relative rotation of the collars is sufficient to open the contacts 52 and 54 is had, the pin 40 will take up the slack of slot 38 and thereafter cause the cam shaft 16 to be directly turned by the knob 26, it being understood that so long as any turning torque in the advance direction is applied to the knob 26, the contacts 52 and 54 are held open. As soon as such torque is discontinued, the contacts close.

Shifting from one set of alternate cams to the other is had by axially moving the shaft 32 through a thrust sleeve and cam mechanism 74 actuated by the concentric knob 76. Such knob is splined on a sleeve 78 surrounding shaft 32 and passing through the frame bearing collar 80. The sleeve is provided with a spiral cam track 82 co-acting with a follower end 83 of a set screw 84, so that as the sleeve 78 is rotated, it is caused to move axially. The shaft 32 is provided with thrust washers 86 and 88 at either end of the sleeve 78, so that the axial movement of the sleeve 78 axially moves the shaft 32; however, without rotating the shaft. Axial movement of the shaft 32 is transmitted to the shaft 16, so as to shift one set of alternate cams out from under the cam followers 14 and place the other set in operative position with respect to the cam followers. Pinion 22 is elongated to permit axial movement of shaft 16 without disengagement. A U-spring 90 mounted on stationary mounting pins 92 and 94 on the end member 96 on the frame 10 is adapted to resiliently embrace one or the other of the shaft grooves 96 in the shaft 16, the ends of the U-spring being resiliently spreadable as the shaft 16 is axially moved to permit the spring ends to shift from one of the grooves 96 to the other. The spacing between such grooves is the same as the spacing between adjacent cams of a pair.

Since the cams have lobes 98 and depressed portions 100 which actuate the cam followers, it is desirable that each of the disk cams have a circular portion, so that the cams of each pair of cams will present angularly aligned circular portions of like diameter so that before one cam is shifted out from under its follower, the other cam can be shifted under the follower, the follower being of a width to bridge the spacing between adja-

cent cams of a pair during shifting. In order to prevent the shaft 16 from being axially moved except when such circular portions of like diameter of the cams of each pair are in engagement with the cam followers, a cam-like interlock comprising a shaft-carried disk 102 and stationary button 104 mounted on the frame end 96 are provided. The cam-like disk has a circular portion 106 of a radius sufficient to prevent the shaft 16 from being moved past the button 104, and is provided with a portion 108 of lesser radius sufficient to clear the button 104. The angularly aligned circular portions of like diameter of the cams of each pair are so angularly coordinated with respect to the other pairs and the reduced radius portion 108 of the interlock disk 102 so as to prevent axial shifting of the cam shaft except when all of the cam followers are riding on one of the circular portions adjacent to a circular portion of like diameter of the adjacent cam of the pair. Axial shifting of the cams will thus normally take place when all cam followers are held in their intermediate open circuit positions as illustrated in Figure 6, although it will also appear that if the cams of one or more pairs have angularly aligned depressed or raised portions of like diameter, in angular alignment with the aligned like diameter portions of the cams of each of the other pairs of cams, axial shifting may also be permitted, and the interlock cam may be so constructed to permit shifting under such circumstances if desired. The interlock will be so designed as to prevent shifting whenever a finger is in contact with one cam of a pair at a point having a certain radius, and the adjacent portion of the other cam of the pair is of a different radius.

From the foregoing description, it will appear that a cycle timer is provided affording more than one automatic cycle, and in which alteration of each cycle may be effected manually as desired. At the same time, when such manual advance is effected, all circuits which would normally be established by the cams during the period eliminated by manual advance, are opened for the brief moment such cams are being advanced. Assurance that no false energization of any circuit not required is thereby had, by merely placing contacts 52 and 54 in circuit with the source of power.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In an appliance timer, a frame, a cam shaft rotatably and slidably mounted therein, a plurality of disk cams mounted on said shaft and arranged in pairs, the cams of each pair being uniformly spaced, cam-engaging fingers mounted on said frame, said fingers having a cam-engaging face of a width sufficient to bridge the spacing between cams of a pair; one for each pair of cams and adapted to engage either cam; a timer motor for driving said shaft, resilient means for holding said shaft in either one of two axial positions spaced approximately the same as the spacing between cams of a pair, said cams having arcuate portions angularly aligned with respect to one another with the said cam portions of each pair of like radius, and interlock means carried by said shaft and frame for preventing axial move-

ment of the shaft when said arcuate portions are out of contact with said fingers.

2. In an appliance timer, a frame, cam shaft means rotatably and slidably mounted therein, a plurality of disk cams mounted on said shaft means arranged in pairs, the cams of each pair being uniformly spaced, cam-engaging fingers mounted on said frame, said fingers having a cam-engaging face of a width sufficient to bridge the spacing between cams of a pair, one for each pair of cams and adapted to engage either cam, a timer motor for driving said shaft means, resilient means for holding said shaft means in either one of two axial positions spaced approximately the same as the spacing between cams of a pair, said cams having arcuate portions angularly aligned with respect to one another with the said cam portions of each pair of like radius, interlock means carried by said shaft means and frame for preventing axial movement of the shaft means when said arcuate portions are out of contact with said fingers, a thrust sleeve rotatably mounted on said shaft means, and camming means coacting between said sleeve and frame, whereby on rotation of said sleeve, said shaft is moved axially.

3. In an appliance timer, a frame, cam shaft means rotatably and slidably mounted therein, a plurality of disk cams mounted on said shaft means arranged in pairs, the cams of each pair being uniformly spaced, cam-engaging fingers mounted on said frame, said fingers having a cam-engaging face of a width sufficient to bridge the spacing between cams of a pair, one for each pair

of cams and adapted to engage either cam, a timer motor for driving said shaft means, resilient means for holding said shaft means in either one of two axial positions spaced approximately the same as the spacing between cams of a pair, said cams having arcuate portions angularly aligned with respect to one another with the said cam portions of each pair of like radius, and interlock means carried by said shaft means and frame for preventing axial movement of the shaft means when said arcuate portions are out of contact with said fingers, said means comprising a cam-supporting shaft, and a manual control shaft, and a resiliently biased lost motion connection therebetween, contacts carried by said shafts and held closed by said resiliently biased lost motion connection, whereby rotation of said manual control shaft against the resilient bias of said connection opens said contacts.

4. In an appliance timer, a frame, cam shaft means rotatably mounted therein, a plurality of disk cams mounted on said shaft, cam-engaging fingers mounted on said frame, a timer motor for driving said shaft, said shaft means comprising a cam-supporting shaft and a manual control shaft, and a resiliently biased lost motion connection therebetween, contacts carried by said shafts and held closed by said resiliently biased lost motion connection, whereby rotation of said manual control shaft against the bias of said connection opens said contacts.
